A. E. COY.
TELEPHONE TRANSMITTER.
APPLICATION FILED MAR. 20, 1920.

1,403,593.

Patented Jan. 17, 1922.

UNITED STATES PATENT OFFICE.

ALBERT E. COY, OF CHICAGO, ILLINOIS.

TELEPHONE TRANSMITTER.

1,403,593.

Specification of Letters Patent. Patented Jan. 17, 1922.

Application filed March 20, 1920. Serial No. 367,560.

To all whom it may concern:

Be it known that I, ALBERT E. COY, a citizen of the United States, residing at Chicago, in the county of Cook and State of

5 Illinois, have invented certain new and useful Improvements in Telephone Transmitters, of which the following is a specification.

The invention relates to improvements in 10 portable telephone transmitters.

One of the objects of the invention is to provide an improved instrument for use with a sound amplifying system to be used by persons who are partially deaf.

15 Another object is to provide an improved means for mechanically connecting the transmitter with a case enclosing the standard battery and adapting the electric terminals of a transmitter for co-operation with 20 the contact terminals of a standard battery.

Another object is to improve the transmitter casing to increase the sensitiveness and clearness of transmission.

Another object is to provide an improved 25 form of transmitter casing especially adaptable for a battery casing of standard form.

Another object is to provide a new and improved form of cover, or closure, for the transmitter, providing an air chamber of 30 peculiar character between the diaphragm and the inner surface of the cover, and providing a means for concentrating the sound waves that impinge upon the cover near the center thereof.

35 Other, further and more specific objects of the invention will become more readily apparent, to persons skilled in the art, from a consideration of the following description, when taken in conjunction with the 40 drawings, wherein:—

Fig. 1 is a front view of the instrument with the battery-containing casing open, showing a two cell dry battery of standard make therein.

45 Fig. 2 is a section taken on line 2—2 of Fig. 1.

Fig. 3 is a section taken on line 3—3 of Fig. 2.

Fig. 4 is a section taken on line 4—4 of 50 Fig. 2.

Fig. 5 is a section taken on line 5—5 of Fig. 2.

In all the views the same reference characters are employed to indicate similar 55 parts.

10 is a casing or container for a battery

11. The battery may contain a plurality of cells, such as 12 and 13. The container is oval in shape to correspond with the transverse sectional outline of the battery and is 60 hinged, preferably, at one of its sides, as at 14, with a cover, or closure 15, and is provided with snap members 16 and 17 to latch the cover or closure to the container 10. The battery box, or container, similar in general 65 outline to that described, is used with the standard battery 11.

In the disclosed embodiment, to one end, to-wit: end 18, the transmitter casing 19 is secured. The transmitter casing, preferably, round in outline is provided with a lateral projection 20. It is provided also with a round or circular top, or cover 21, that is secured to the casing by screw threaded engagement 22, as usual in devices of this 75 character.

The part 20 of the transmitter casing is flat on its bottom surface, as at 23, for direct support upon the flat end wall 18, of the 80 battery casing 10.

The transmitter casing 19, contains a carbon disk 24, and a solid back button 25 is supported in the casing by a metallic structure consisting of the strip 26, and screws 27.

The projecting portion 20, of the transmitter casing, is provided with two spaced-apart threaded tubes 28 and 29. The transmitter disk is connected by a wire 41 that leads to a receiver and the button 25 is connected to the tube 38 by a wire 31 and 90 screws 32.

The lower ends of the tubes 28 and 29 are also threaded and a screw 34 passes through the wall 18 of the battery casing into the tube 28 and also through a contact spring 95 35. The screw 36 is insulated from the casing by an insulating disk 37 and it supports a spring blade contact 38 for cooperation with a similar blade contact 39 of the stand and battery 11, so that when the battery 11 is placed within its casing 10, the terminal 40, of the battery, makes spring yielding contact with the spring blade 35, and the terminal 39, of the battery, makes similar contact with the blade 38 thereby completing 105 the circuit through the battery by the act of placing the battery in its casing.

Two circuit wires from the transmitter of the system, wires 41 and 42, pass through an opening 43, made in the projecting portion 20 of the transmitter casing. This opening is between the back of the transmit-

ter casing and the cover 21 and below the cover. The wire 41 is connected to the diaphragm 24, while the wire 42 is connected to the screw 33. By this means the carbon button and diaphragm of the transmitter is connected properly to the wires 41 and 42 that lead to the receiver.

The cover 21 is provided with a concave wall 44 having a central perforated zone 45, surrounded by an annular ring-like structure 46 projecting from the inset portion of the wall to the front of the instrument. This wall, 46, has a tendency to concentrate the sound waves that impinge upon the cover or closure 21, and to direct them more forcibly against the underlying diaphragm. The structure also provides a peculiar sound chamber 47, being deeper near its periphery than its central portion. For reasons for which I cannot account, the peculiar form of the chamber enhances the operative effectiveness of the instrument, rendering the transmission more sharply and distinctly effective.

The entire structure is devoid of outside terminals, screws and contacts, that render such devices so objectionable for general use for the purpose for which this instrument is intended.

While I have herein shown a single embodiment of my invention, it will be manifest to persons skilled in the art, that many changes may be made in the general arrangement and configuration of the parts within the scope of the appended claims.

Having described my invention what I claim as new and desire to secure by Letters Patent is:—

1. In combination a transmitter casing

having a lateral projection; a battery casing secured thereto, conductors extending between both casings, clamping screws carried by the conductors in both casings, said transmitter casing having an opening therefrom terminating on one side of the lateral projection and conductors passing through said opening into the transmitter casing.

2. In a device of the character described, a generally round transmitter casing with a lateral integral projection terminating in a substantially flat surface; a battery casing having a substantially flat contacting end wall; two spaced-apart screw threaded terminal members, extending through said projection to the contacting wall; a terminal plate for each member, within the battery casing, adapted for connection with the terminals of a standard battery, by the act of placing said battery in the casing and clamping means engaging the threaded terminals to hold the casings together.

3. In a device of the character described the combination of a telephone transmitter casing and an attached battery casing, the transmitter casing being generally round in outline and having a lateral integral projection for support on the battery casing; two threaded conducting members passing through said projection to the adjacent wall of said battery casing for connection with terminals in the interior thereof; means, cooperating with said members to hold the casing together and clamping means within the respective casings to include said members in circuit.

In testimony whereof I hereunto subscribed my name.

ALBERT E. COY.
